UNITED STATES PATENT OFFICE.

ROBERT A. MOORE, OF DETROIT, MICHIGAN.

SURFACE-COATING APPARATUS.

1,306,830.

Specification of Letters Patent. Patented June 17, 1919.

Application filed February 18, 1918. Serial No. 217,736.

To all whom it may concern:

Be it known that I, ROBERT A. MOORE, a citizen of the United States, and a resident of Detroit, county of Wayne, and State of Michigan, have invented a new and useful Improvement in Surface-Coating Apparatus, of which the following is a specification, the principle of the invention being herein explained and the best mode in which 10 I have contemplated applying that principle, so as to distinguish it from other inventions.

The present invention, relating, as indicated to surface coating apparatus, is particularly concerned with a device which may be used for applying a coat of liquid or semi-liquid material, such as paste, to a desired surface, and is more particularly concerned with the applying of a filling coat of putty 20 to a surface before painting, although obviously the same apparatus may be used for applying other materials, such as liquids and semi-liquids for other purposes. A further object of the invention is the provision in 25 such an apparatus of means for permitting the operator to continuously and manually control the supply of the coating material to the surface being gone over. A further object of the invention is the provision of an 30 extremely simple and easily operated device for carrying out the purposes above described. To the accomplishment of the foregoing and related ends, said invention, then, 35 consists of the means hereinafter fully described and particularly pointed out in the claims.

The annexed drawing and the following description set forth in detail certain mechanism embodying the invention, such description 40 closed means constituting, however, but one of the various mechanical forms in which the principle of the invention may be used.

In said annexed drawing:—

Figure 1 is a longitudinal section through 45 the device when pressed against a surface and in operative position with respect thereto; Fig. 2 is a transverse section on the line 2—2, Fig. 1; Fig. 3 is a similar transverse section on the line 3—3, Fig. 1; Fig. 4 is a 50 similar section on the line 4—4, Fig. 1; and Fig. 5 is a front view of the device illustrating a modified type of spreading knife, which shall be described in detail herein- 55 after.

In the form illustrated in the drawing the device is constructed for applying a filling

coat of putty to a surface 1, the device consisting of a box-like chamber 2 serving as a reservoir for the material to be supplied to the surface. This material is contained in 60 the triangular-shaped reservoir 3 and is fed from this reservoir through a discharge nozzle 4 between a spreading knife 5 and the forward lower edge 6 of the casing 2. The spreading knife 5 is removable and is held 65 with any desired degree of tension against the edge 6 by means of a set screw 7 when the device is not in use, but is pressed away from the edge 6, when forced against the surface to be coated, a sufficient distance to permit 70 the material to be fed in a thin coat between these two edges. The thickness of the coat applied may of course be varied by varying the pressure of the device against the surface which raises the knife 5 a greater distance from the edge 6, and also by increasing 75 the supply of material fed to this discharge opening by the means which will now be described.

The chamber 2 is normally closed by 80 means of a cover 8, which is pivoted about the rear end of the casing 2 by means of a pin 9, which also serves as a pivot or hinge for an ejecting member in the form of a plate 11. The ejecting member 11 is snugly 85 fitted into the casing 2 so that it contacts the side of the casing and the forward end to prevent any leakage of material from beneath the plunger to the top of the casing. This plate 11 is preferably constructed with 90 a washer 12 consisting of a strip of leather fastened between upper and lower plates 13 and 14 respectively, while the forward end 95 30 of the chamber 2 is curved to the arc of a circle drawn at that distance from the hinge 9 as a center, and thus the end of the plate 11 is maintained in contact with the forward end of the casing throughout its entire range of movement. The forward end of the plate 11 may be curved upwardly, as indicated in Fig. 1, to secure a slightly better feeding action at the lower part of its stroke or movement when it approaches the bottom 100 of the casing 2.

Pivots mounted in the plate 11 is a rod 105 15, which extends upwardly beyond the sides of the casing 2. This rod is hinged by means of a pin 16 extending into the leather washer between the plates 13 and 14 and allows the rod a considerable movement to either side 110 of a line drawn at right angles to the plane at the bottom of the casing 2. The rod 15

extends through an aperture in the cover 8 for the chamber 2 and is engaged by means of a handle member 17, which is pivoted about a bar 18 formed as a part of the forward end of the casing 2. Pressure downward on the handle member 17 forces the ejecting member or plate 11 downward toward the bottom of the casing 2 and thus forces the material therein through the opening 4 to the discharge nozzle between the plates 5 and 6, and the handle is of sufficient length to afford a considerable leverage in the depression of the plate 11 so that it is an easy matter for the workmen to force even such material as putty from the casing 2 through the nozzle. The method of operation will be readily understood from the foregoing description of the device. The workman grasps the casing usually in both hands, pressing slightly on the lever 17, and pressing the spreading knife 5 against the surface until it opens the nozzle sufficiently to permit the desired amount of material to be discharged. The device is then drawn over the surface to be covered and a thin coat of material is applied to the surface by means of the spreading knife 5.

In case it is desired to form a ridge of the material on the surface that is being treated it can be done by cutting an opening 20, such as shown in Fig. 4, at any desired point in the spreading knife and the material will then issue from this opening. If the opening is a semi-circle as shown in Fig. 4 a semi-circular ridge of the material will be spread across the surface and the device may be used for this purpose in tuck pointing the joints between brick with cement.

It is unnecessary to point out the various uses for my device as these will readily suggest themselves to those skilled in the various arts. It will be recognized that in the device the material may be spread evenly and rapidly and may be constantly controlled by the operator through his pressure of the device against the surface and his operation of the handle.

Other modes of applying the principle of my invention may be employed instead of

the one explained, change being made as regards the mechanism herein disclosed, provided the means stated by any of the following claims or the equivalent of such stated means be employed.

I therefore particularly point out and distinctly claim as my invention:—

1. In apparatus of class described, the combination of a reservoir, a discharge opening leading therefrom, and adapted to be opened by pressure against a surface to be coated, a pivoted ejecting member mounted in said reservoir and adapted to force material therefrom through said discharge opening, and a pivoted handle connected to said ejecting member and adapted to operate the same.

2. In apparatus of class described, the combination of a reservoir, a discharge opening leading therefrom, and adapted to be opened by pressure against a surface to be coated, a pivoted ejecting member mounted on said reservoir, a rod attached to said member, and a handle pivotally attached to said reservoir and extending substantially parallel thereto, said handle engaging and being adapted to actuate said rod to operate said ejecting member.

3. In apparatus of the class described, the combination of a reservoir, a discharge opening leading therefrom, a plate hinged to said reservoir adjacent to one bottom end thereof, said plate being provided with packing material snugly contacting the sides of said reservoir, and means adapted to swing said plate about its axis toward the bottom of said reservoir.

4. In apparatus of class described, the combination of a reservoir, a discharge opening leading therefrom, and adapted to be opened by pressure against a surface to be coated, a pivoted ejecting member mounted in said reservoir and adapted to force material therefrom through said discharge opening, and double power multiplying connections for operating said ejecting member.

Signed by me, this 11th day of February, 1918.

ROBERT A. MOORE.
